CREEL

Arthur A. Atkins, Coventry, Harry M. Averns, Allesley, Coventry, and Arthur Walker, Coventry, England, assignors to Courtaulds Limited, London, England, a British company

Application January 24, 1950, Serial No. 140,234
In Great Britain February 3, 1949

3 Claims. (Cl. 242—131)

1

This invention relates to creels.

In one type of creel used hitherto, for example in warping, the bobbins or other yarn packages, usually of the order of 500 or more, are mounted on pegs which are arranged in tiers on the creel frame and each separate yarn is passed first through a guide eye within the creel frame, then between a pair of horizontal tension discs and thence, with the aid of one or more guides and tension bars, through a reed to the collecting device, for example a swift or a beam.

When warping certain types of textile yarns, there are limits to the practical speed at which the yarns can be wound on the swift or beam. One limiting factor is the tendency for the yarns to become electrified as a result of rubbing, for example on thread guides, this tendency being more troublesome at higher speeds. When the swift or beam is stopped or rotated backwards slightly, the electrified yarns are disturbed as a result of electrical attraction or repulsion, and so tend to come into contact with the creel. The electrified yarns also tend to attract dust and dirt. When using low twist yarns, there will also be mutual repulsion of the individual filaments of the yarn, with the result that filaments are more susceptible to damage.

The object of the present invention is to permit the warping of yarns, particularly low twist yarns, at increased speeds whilst substantially avoiding the above-mentioned drawbacks.

The present invention comprises a creel in which the frame is provided near each peg with a tension device, one for each peg, and the front of the creel (that is the face of the creel nearest the collecting device) is provided with a like number of tension devices so arranged that each yarn, on being withdrawn from its bobbin and passed to the collecting device is held substantially horizontal between the two tension devices even when the collecting device is stationary or has been rotated backwards slightly.

Where the yarns towards the back of the creel have a long path to travel before reaching the tension devices at the front of the creel, it may be desirable to support the yarn between the two tension devices, for example by providing intermediate thread guides such as eyes, pigtail guides or combs. Yarn guides, for example eyes, pigtail guides, U or inverted U guides are also provided beyond the tension devices at the front of the creel in order to maintain the yarns horizontal as they pass through the tension device; the yarns are then led to the swift or beam in accordance with standard practice.

2

The invention also includes a combined tensioning and guiding device for use on a creel according to the invention, comprising at least three fixed pins spaced to act as a guide for the yarn and to hold against transverse displacement tensioning discs having a central hole to permit the discs to be dropped over the fixed pins. The yarn is preferably passed between two tension discs each of which is loosely fitted over the pins. Additional weighting discs or washers may be placed on the upper disc.

In a preferred form of creel according to the invention, two sets of combined tensioning and guiding devices as described are provided on the creel, one set being provided on the frame near the pegs and the other set being provided in tiers at the front of the creel.

In the creel with the combined tensioning and guiding devices according to the invention, the yarn is withdrawn from the yarn package and passed directly between the tension discs; that is to say there are no separate guides provided between the yarn package and the discs. In this manner the time required for threading up the creel is considerably reduced.

The preferred number of pins in each tensioning and guiding device is three, the three pins being conveniently arranged at the corners of an equilateral triangle; more than three pins may be used if desired. The pins and especially the pins coming into contact with the yarn are preferably constructed from material having a good resistance to wear; suitable materials are hardened and polished stainless steel, for example as used for needle roller bearings, chromium plated steel, tungsten carbide, synthetic sapphire and synthetic ruby. The pins are preferably rounded off at the top so that during threading up, the yarn slips readily between the pins without damaging the separate filaments of the yarn. The use of these three or more pins in this manner serves to locate the tension discs and prevent sideways displacement.

The tension discs used may be any of the known types of discs used for this purpose, in which the weight of the top disc or discs determines the tension on the yarn. For example the discs may be made of aluminum, the edges of the discs being bevelled off or turned up so that the yarn is naturally guided between the discs by the bevelled or upturned edges. The top disc or discs may remain stationary during the withdrawal of the yarns or may be rotated by the yarn if desired.

One example of a creel in accordance with the

present invention is illustrated in the accompanying diagrammatic drawings in which

Fig. 1 is a plan of the creel with parts broken away;

Fig. 2 is a side elevation of a creel embodying the invention with parts broken away;

Figures 3 and 4 are a side elevation and a plan respectively of one of the tension devices near the creel pegs, the upper tension disc being shown in section in Figure 3.

In the creel shown in the drawings a series of bobbins 1 are mounted on creel pegs 2 on a frame 3 in the usual manner with four tiers of bobbins and pegs. Yarns 4 are withdrawn as a balloon from the bobbins 1 and each yarn is passed through one of a series of tension devices 5 mounted on a bar 6 which conveniently forms part of the creel frame. From the tension devices 5 each yarn 4 is passed horizontally to one of a second series of tension devices 7, then, still horizontally, to one of a series of guide eyes 8 in a fixed rail 9 and thence at an angle (see Figure 2) to the swift or beam (not shown) in accordance with the standard practice. All the yarns 4 therefore maintain a substantially horizontal path from the time they pass through the tension devices 5 until they pass through the eyes 8.

The construction of the tension devices 5 is shown in Figures 3 and 4. A turret 10 is secured by a bolt 11 to the bar 6 and three pins 12, 13, 14 are fixed in the turret 10 at the corners of an equilateral triangle. The top of the pins are rounded off as shown (Figure 3) to reduce or prevent damage to the yarn during threading up. Two tension discs 15, 16 are dropped over the pins so that they fit loosely over them. The edges of the discs 15, 16 are turned up as shown in Figure 3 so that the yarn is naturally guided between the two discs.

The tension devices 7 are constructed in the same way as the devices 5 and are mounted in staggered relationship on a horizontal bar 17 supported by fixed vertical posts 18 at the ends of the bars 17.

If the creel is very long it is desirable to support the yarns coming from the back of the creel between the tension devices 5 and 7, for example by a series of eyes 19 in a bracket 20 secured to the bar 6.

The actual path of the yarn between the pins of the tension devices 5 and 7 may be varied; for example the yarn may be brought into contact with one or with two of the pins in order to produce the necessary deflection. The position of the pins relative to the yarn may be adjusted as required by loosening the bolt 11, rotating the turret 10 to the desired position and tightening the bolt 11.

Although the invention has been described as applied to a creel in which the yarn packages are supported on a portion of the frame which is substantially at right angles to another portion of the frame from which the yarn exits to a swift or beam in accordance with standard practice, it will be understood that the invention is applicable to creels wherein the package supporting part is located differently with relation to the discharge part or the exit rail than in the arrangement illustrated in the present drawings. The invention is for use in connection with any creel wherein the package supporting part is spaced from the discharge part of the frame to such an extent that the relatively long lengths

of yarn would have a tendency to sag and tangle in the absence of the means provided by the present invention.

What we claim is:

5 1. A warping creel comprising a frame having a package supporting part and a discharge part, said package supporting part being spaced from said discharge part, relatively long lengths of yarn running between said parts having a 10 tendency to sag and tangle with one another, a number of pegs arranged in tiers on the package supporting part of the frame with a plurality of pegs in each tier for supporting yarn packages, a first set of tension devices, like in number to 15 the pegs, mounted on the package supporting part of the frame, one tension device being located in close proximity to each peg for that peg, the creel being adapted to permit the yarns to pass directly from the yarn packages to said first set of tension devices, in combination with a number of horizontal bars at the delivery part of the creel in alignment with the tiers of pegs and spaced from said pegs, and a second set of tension devices like in number to the first set 20 mounted on the horizontal bars, each yarn from a package being held in tension substantially horizontally between its tension device near the pegs at the package supporting part and a corresponding tension device on the horizontal bars of the discharge part.

2. A creel as claimed in claim 1 wherein each tension device near the creel pegs comprises at least three fixed pins spaced to act as a guide for the yarn and to hold the yarn against transverse displacement and a pair of tension discs loosely mounted one above the other on said pins, at least one tensioning disc having a central hole to permit it to be dropped over the fixed pins and to bear frictionally on the yarn with the force of 30 its weight.

3. A creel as claimed in claim 1 wherein the tension devices, both near the creel pegs and also at the front of the creel each comprises at least three fixed pins spaced to act as a guide for the yarn and to hold the yarn against transverse displacement, and a pair of tension discs loosely mounted one above the other on said pins, at least one tensioning disc of each tension device having a central hole to permit it to be dropped over the fixed pins and to bear frictionally on the 35 yarn with the force of its weight.

45 4. A creel as claimed in claim 1 wherein the tension devices, both near the creel pegs and also at the front of the creel each comprises at least three fixed pins spaced to act as a guide for the

50 yarn and to hold the yarn against transverse displacement, and a pair of tension discs loosely mounted one above the other on said pins, at least one tensioning disc of each tension device having a central hole to permit it to be dropped over the fixed pins and to bear frictionally on the 55 yarn with the force of its weight.
